CHAIR OR THE LIKE

Charles R. Pollock, Brooklyn, N.Y., assignor to Knoll
Associates, Inc., New York, N.Y., a corporation of
New York

Filed June 9, 1961, Ser. No. 65,528

Term of patent 14 years

(Cl. D15—1)

FIG. 1 is a perspective view of the chair embodying my new design;

FIG. 2 is a front elevation of the chair taken at the right in FIG. 1.

The design is characterized by the particularly configured unitized seat and back rest in combination with the leg and brace arrangement, all as shown.

I claim:

The ornamental design for a chair or the like, as shown and described.
